UNITED STATES PATENT OFFICE.

WILLIAM GOULD BROKAW, OF PARIS, FRANCE.

CARTRIDGE CONTAINING COMPRESSED OR LIQUEFIED GAS FOR INFLATING LIFE-PRESERVING BELTS, PNEUMATIC TIRES, AND OTHER PURPOSES.

1,264,003.

Specification of Letters Patent. Patented Apr. 23, 1918.

Application filed October 14, 1916. Serial No. 125,758.

To all whom it may concern:

Be it known that I, WILLIAM GOULD BROKAW, a citizen of the United States, whose post-office address is 41 Boulevard Haussmann, Paris, France, have invented new and useful Improvements in Cartridges Containing Compressed or Liquefied Gas for Inflating Life-Preserving Belts, Pneumatic Tires, and other Purposes, of which the following is a specification.

The present invention relates to devices which are charged with compressed or liquefied air or gas, and used for inflating life-preserving belts, pneumatic tires and, in general, in all cases where it is desired to deliver air or gas for any desired purpose.

As in devices of the kind hitherto proposed, the device herein described utilizes the expansive force of the liquefied gas possessing, at the ordinary temperature, a sufficiently low tension to enable its being preserved in a liquid state in a suitable container.

The herein described cartridge differentiates itself more particularly from hitherto proposed devices in that it is not necessary, when it is desired to make use of it, either to unscrew a plug, or slacken a screw, or to operate a lever or other like member in order to bring about the escape of gas. In other words, the cartridge is not provided with any special opening or closing contrivance.

Broadly speaking, the invention consists, primarily, in forming a glass container, in such a manner that the closing thereof is obtained by sealing the glass itself, while the opening is obtained by merely breaking, by means of the hand, a determined portion of the container. The said breakage can be performed with the greatest simplicity and, when once effected, it immediately gives rise to the escape of the gas therein contained.

Furthermore, the invention consists in a special sheath or case for the reception of the cartridge.

The accompanying drawing illustrates, by way of an instance, a cartridge constructed in accordance with the present invention.

Figure 1 is a longitudinal section of the invention and Figs. 2 and 3 are views of life-preserving belts to be used in connection therewith.

55 a represents a matrass having a neck b.

It is introduced in a sheath c of metal or other suitable material, hermetically closed at the bottom by a plug d and provided, at the top, with a nozzle e to which is connected, by a ligature or other suitable air-tight means, a tube of somewhat thick rubber f, acting to protect the neck b against accidental fracture. Linings g of rubber or other suitable substance protect the matrass against shocks.

The matrass, which contains air or a suitable liquefied gas, such for instance as sulfurous anhydrid, is sealed at its end by means of a lamp or blow pipe. The neck b can be easily broken by the hand.

70 Into the end of the rubber tube f is placed a nozzle h held in place by a ligature or other equivalent means. The said nozzle, which may be of any appropriate kind, is formed with a screw-threaded hole i by 75 which it can be connected either to a nozzle j on the life-preserving belt k, shown in Fig. 2, or to a pneumatic tire, or to any other contrivance to be inflated or to be supplied with the air or gas stored up in the matrass. 80

The diameter of the hole i is preferably smaller than that in the neck b, so that when broken, the latter cannot be carried out of the tube f along with the gaseous current. For greater safety, the nozzle h may be lined 85 or provided with a perforated disk or wire-cloth l. Finally, the neck b is protected against breakages when the device is not to be used, by a suitable cap n which can be readily removed.

90 The operation is as follows. The cartridge is connected by means of the nozzle h to a life-belt k for instance, by using the nozzle j into which is fitted, as usual, a check-valve which will let the gas pass during the inflating operation, but will prevent any escape of the gas when once the inflating operation is completed. The operation is the same as in the case of a pneumatic tire.

100 The operation may, however, be performed in a different manner in the case of life-belts in that, instead of causing the cartridge to act from the outside, as hereinbefore described and as heretofore proposed, it 105 may be caused to act from the interior by placing it inside the belt k¹, this belt being illustrated in Fig. 3. For that purpose, it would be sufficient to bore a hole in the wall of the belt, to then introduce the charged 110

cartridge and finally seal the hole hermetically by means of a rubber or other disk m , which is cemented on or applied in any other suitable air-tight manner. In such case, the 5 cartridge is contained freely inside the belt, instead of being connected thereto, as hitherto proposed, by a nozzle, the objection to the latter being that it may not prove air-tight. In order to inflate the belt, it is then 10 sufficient, at the time of danger, to break the neck b , as already described.

Independently of the above mentioned 15 purposes for which this special arrangement of cartridge is more particularly intended, it is to be understood that, among other uses, it may also be employed for inflating footballs, india rubber animals or 20 toys and, in general, for all other applications.

20 I claim:

1. The combination of a sealed glass cartridge having a frangible portion with an air-tight casing completely inclosing the same and yieldable to permit fracture of the 25 cartridge.

2. The combination of a sealed glass cartridge having a frangible portion and an air-tight casing completely inclosing the same and yieldable to permit fracture of the 30 cartridge, said casing having means adapted to be coupled to a device to be inflated.

3. The combination of a sealed cartridge having an elongated relatively small frangible neck, and an air-tight casing completely 35 inclosing the said cartridge and yieldable to permit the neck to be fractured.

4. The combination of a sealed glass cartridge having a frangible portion and an air-tight bendable casing completely inclosing 40 the same and having a strainer and a screw-threaded head to be coupled to a device to be inflated.

Copies of this patent may be obtained for five cents each, by addressing the "Commissioner of Patents, Washington, D. C."

5. The combination of a sealed glass cartridge having a frangible portion and an air-tight casing completely inclosing the 45 same, the neck of said casing being composed of semi-rigid material, and a screw-threaded head adapted to be coupled to a device to be inflated.

6. The combination of a sealed glass cartridge and an air-tight casing completely covering the same, the body of the said glass cartridge being securely held in place in the said casing by suitable spacers, the neck of said cartridge being frangible and having a 55 yieldable casing, and the head of said casing constructed to be coupled to a device to be inflated.

7. The combination with a sealed glass cartridge comprising a body and an elongated frangible neck, of an air-tight casing completely covering the body of said cartridge, spacers between said body and casing, the frangible neck of said cartridge having a casing composed of semi-rigid material which is adapted to permit of fracturing the neck of said cartridge, and means 60 for attaching said casing neck to a device to be inflated.

8. The combination of a sealed glass cartridge and an air-tight casing, the neck of 70 said casing being bendable, and provided with a cover to protect against accidental bending of the same, and the head of said casing constructed to be coupled to a device 75 to be inflated.

In witness whereof, I have hereunto set my hand this 25 day of Sept., one thousand nine hundred and sixteen, in presence of two subscribing witnesses.

WILLIAM GOULD BROKAW.
